METHOD AND APPARATUS FOR MAKING
PILES

Werner W. Edman, Lakewood, Ohio

Application November 16, 1931
Serial No. 575,392

16 Claims. (Cl. 61—57)

The present invention provides a novel method and apparatus for forming concrete piles in situ at the location of their use, whereby there will be formed, ready-placed, a concrete structure of such density and compactness as to resist disintegrating influences until the concrete has completely hardened. The operation is such that these results are obtained in a manner permitting the immediate removal of the forms employed, there being left a self-supporting concrete structure of the characteristics above referred to.

This invention therefore provides a method whereby structures of this kind are formed in a quicker manner than heretofore, and it also embraces a novel form of apparatus for carrying out this process, the apparatus being of a very simple construction, easily fabricated and easily manipulated. The advantages of the present invention will be apparent from consideration of the detailed description which will be hereinafter given.

In general, the invention comprises the provision of forms for molding the concrete in position at its place of use. These forms conveniently comprise an outer shell, or mold, with a cooperating compression member which enters into the outer shell, and compresses the concrete mixture placed therein by subjecting the mixture to high compression resulting from the impact of driving blows from a pile driving machine of generally the usual type.

In practicing the invention, these forms or molds are assembled one within the other, the inner mold being hollow and having a slightly upwardly converging formation, the base having the greatest diameter, and fitting flush against the inside walls of the outer form, which is cylindrical, and simply holds the concrete in place while the pressure is applied thereto. Both forms are of suitable material of required strength to withstand the pressure, such as steel, and are cast with flanges adjacent the upper end of each, so that they may be grappled with a suitable tool for removal of the forms when desired.

After assembling these forms, the aforesaid flanges of the inner mold engage the top of the outer form, and the two forms are driven together into the ground at the location where the pile is to be employed. The flush engagement of the large end of the inner mold with the inner surface of the outer form prevents the entry of dirt therein, the said end of the inner mold being provided with a removable cap, or cover,

which prevents access of dirt to the interior of the inner mold.

When the two forms have been driven into position, the inner form is grappled and pulled entirely out from the outer form, suction being prevented by providing the cap with means for equalizing the air pressure on the inside and outside of this inner mold as it is withdrawn; therefore, any clogging of the outer form by earth and the like being drawn therein by this removal of the inner mold, is prevented. Such means will be more particularly described hereinafter.

After the inner mold has been withdrawn, concrete is poured into the outer form to the desired depth. The inner member is again inserted, its closure cap having been removed, and driven into the outer form by impacts from the driving machine as far as the inner mold can enter. This operation compresses the concrete into the inner mold, under such pressure as will make the resulting pile self-sustaining and erosion-resistant until it sets, and permits the immediate withdrawal of the forms, leaving the pile formed in situ in condition where it can harden without damage and without external rigid support.

The invention will be now readily understood by reference to the accompanying drawings, in which—

Figure 1 is a somewhat diagrammatic and fragmentary illustration of the manner in which the forms are manipulated, showing the withdrawal of the inner mold after positioning, the outer form being shown in place driven into the ground.

Figure 2 is a longitudinal sectional view through the forms in assembled relation.

Figure 3 is a fragmentary elevation, partly in section, showing the concrete compressed to form the finished pile, the inner mold being partially removed.

Figure 4 is a top view of the completed pile with the forms removed.

Figure 5 is an elevation showing the shape of the completed pile.

Figure 6 is a sectional view on the line 6—6 of Figure 3, looking downwardly in the direction of the arrows.

Figure 7 is a sectional view on the line 7—7 of Figure 3, looking upwardly in the direction of the arrows.

Figure 8 is a fragmentary sectional view through a desirable form of a cap or plug used

for covering the lower end of the inner form member.

Figure 9 is a bottom view of the cap of Figure 8.

5 Figure 10 is a sectional view taken along the line 10—10 of Figure 2, looking downwardly in the direction of the arrows.

Referring first to the construction of the forms, it will be seen that the outer member, or casing, 1 is formed of an open-ended cylindrical casting provided with the flanges or shoulders 2, which in turn have the openings 3 formed therein, which openings constitute a ready means for grappling the form 1 for withdrawal upon 15 completion of the pile.

The inner member 4 may be termed a pressure mold, and this member 4 constitutes also a driving member for the outer casing 1, the member 4 being provided with the outstanding flanges or 20 shoulders 5 which are adapted to engage the upper end of the cylindrical outer member 1. These shoulders 5 are also provided with openings 6 by means of which the member 4 may be lifted out from the member 1 when desired. 25 The upper end of the member 4 is closed by a wooden block or plug 7 which is capped by the member 8 threadedly secured to the upper end of the inner member 4.

The lower end of the inner mold 4 is closed 30 by the cap or plug 9 which is secured in place by the removable securing members 10 and 11 which pass completely through the walls of the mold 4 and the plug in right angled directions through corresponding openings 10a and 11a in 35 the cap and mold, respectively, thus being rigidly mounted in position in the end of the inner mold 4. The mold member 4 has an upwardly tapering configuration, as will be seen in Figure 2, the lower end being the larger, and closely 40 engaging the inner walls of the casing 1.

The forms are manipulated as shown in Figure 1. For driving into position, the mold 4, closed by the cap 9, is placed within the form 1 and the two forms are driven into position by 45 the action of a weight or hammer 12 impacting upon the cap 8, the force being transmitted to the member 1 through the engagement of the shoulders or wings 5 against the top of the said member 1. When the forms have been driven 50 into position, cables are passed over a pair of pulleys 13, of the pile driving machine, and grappling hooks or similar instrumentalities are connected with the opening 6 in the flanges 5, conveniently through cables extending over the 55 pulleys 13 for operation by a suitable source of power. The inner form 4 is thus withdrawn and the concrete is then poured into the outer casing 1.

However, since the member 1 is open-ended, 60 and since the withdrawal of the member 4 therefrom will serve as a piston to produce suction in the member 1 as the part 4 is withdrawn, which might result in sucking up of the material, in which the member 1 is embedded, into the 65 interior of the member 1 to clog the same, it is desirable to form the cap 9 in a manner such as illustrated in Figures 8 and 9, wherein the bottom 9a of the cap is provided with openings 14a extending through the bottom thereof, which are 70 plugged by the members 14, which comparatively loosely fit into these openings; and by making the openings and plugs of a tapering configuration, and by providing a packing of earth or the like between the plugs and their openings, the 75 likelihood of the plugs sticking in the openings

is minimized. When this form of cap is employed, as the inner mold 4 is withdrawn, the suction resulting from the withdrawal will pull the plugs 14 from their seats, and any vacuum which would result from the withdrawal of the 80 plug of the form 4 will be prevented, thus obviating any possibility of the form 1 being obstructed by foreign material drawn up into it.

Upon withdrawal of the mold 4 from the casing 1, concrete is poured into the casing 1 to the required depth, and it will be apparent that when the inner mold 4 is then hammered back into position, a very high pressure will be exerted upon the body of the concrete which will be compressed up into the mold 4 and thereby 85 pressed into a dense, non-porous condition. This pressure may be so great as to cause trouble, and therefore control means are provided.

90 These control means include a movable collar 15 operating upon the upper part of the mold 4, and provided with apertures 16 which are adapted to register with corresponding apertures 17 through the walls of the mold 4. This collar is so positioned that it may be readily turned about the mold 4 by means of a suitably inserted tool, 100 so as to close the openings 17 in an air tight manner, so that there will be no leakage of air during the driving operations upon the concrete. When it is desired to release this pressure for 105 withdrawal of the form 4 upon completion of the pile, the collar 15 is turned so as to engage the openings 16 and 17, whereby the compressed air can flow out into the atmosphere; but in the event that the pressure builds up too much or too quickly, the mold 4 is provided with an adjustable release valve 18, which is so constructed as to release upon the internal pressure building up to a predetermined point. This release valve may be made adjustable so as to operate at any 110 predetermined internal pressure. A further 115 opening 19 may be provided, which permits a ready means for connecting a pressure meter for communication with the interior of the mold 4 during the driving operations, so that there 120 can be an indication or measurement of the pressure existing at any time within the interior of the mold 4. This pressure is to be released before the mold is lifted from the concrete.

When the concrete has been placed within the 125 form 1, and suitably reinforced as indicated at 20, the pressure mold 4 is placed in contact with the concrete and driven in by the pile driving instrumentalities, illustrated by the hammer 12, against the block 12a contacting with the cap 8 of the mold 4, against the concrete so as to compress the same into the pile. By virtue of the 130 upwardly tapering configuration of the mold 4, as the concrete is compressed therein, the resulting pile will be narrower at the top than at the bottom; and to better withstand the pressure, the casing 1 is provided at its bottom with a reinforcing collar 21, riveted thereto at 21a. It will thus be seen that the body of concrete is subjected to an enormous pressure, and, since the mold 4 cannot completely enter the casing 1, 140 the end of the body of concrete will be formed with an enlarged portion, or base, indicated at 22; this representing the space between the bottom of the member 4 and the bottom of the mass of concrete placed in the form 1. Because of 145 the compression, as soon as the pile has been completed, the inner mold 4 may be withdrawn, and then the outer form 1 may be substantially immediately removed, leaving the pile in position 150 in the form of the dense, hard, self-sustaining

column indicated at 23 in Figures 3 and 5. This has the configuration shown in Figure 4, there being an outer periphery 24 and the portion of smaller diameter 25, the tapering configuration 5 of the pile being clearly shown in Figure 5.

When the pile is completed, and the mold 4 is withdrawn, grappling hooks are attached to the flanges 2 by a cable passing over the pulleys 26, and the member 4 is lifted off from around the 10 pile 23, and because of the dense, non-porous character of this pile, it effectively resists all action of moisture or other weathering agents present in its location during the setting or hardening of the concrete.

15 Having thus described my invention, what I claim as new and desire to secure by Letters Patent of the United States, is—

1. A method of forming concrete piles, which comprises sinking a retaining form into position, 20 filling the retaining form to a desired height with concrete, introducing into the retaining form a mold having the form of the finished pile, forcing the mold into the concrete until the concrete is forced up into the mold in a self-sustaining condition, and then removing the mold and retaining form, leaving the pile in completed condition 25 ready for setting.

2. Apparatus for forming concrete piles, comprising the combination with pile driving instrumentalities, of cooperating forms for receiving and molding the concrete, the said forms comprising a concrete receiving form and a mold adapted to enter the receiving form and to be driven by the driving instrumentalities into the concrete placed within the form for compression thereof, reinforcing means for the top of the mold, and grappling shoulders on the form and mold adapted to be grappled for lifting the mold and form from the compressed concrete.

40 3. An apparatus for forming concrete piles, comprising, in combination, a mold for the concrete comprising a hollow member adapted to be driven into a body of concrete for lateral compression of the concrete into the mold under impact of blows imparted by a driving machine, and pressure controlling means in the mold for controlling internal pressure thereof during driving operations.

45 4. An apparatus for forming concrete piles comprising, in combination, a mold for the concrete comprising a hollow member adapted to be driven into a suitable body of concrete for compression thereof into the mold under impact of blows imparted by a driving machine, and controlling means in the mold comprising a rotatable collar on the mold provided with openings therethrough, adapted to be engaged with, and disengaged from, corresponding openings through the mold.

50 5. An apparatus for forming concrete piles, comprising a mold for the concrete, the mold being formed of a hollow pressure member adapted to be driven into a suitable body of concrete for compression thereof into the mold under impact of blows imparted by a driving machine, and controlling means in the mold comprising a pressure operable member actuated by a pressure within the mold of a predetermined value, together with a rotatable collar on the mold provided with openings therethrough, adapted to be engaged with, and disengaged from, corresponding openings through the mold.

55 6. An apparatus for forming concrete piles, comprising a mold for the concrete formed of a hollow pressure member adapted to be driven into a suitable body of concrete for compression there-

of into the mold under impact of blows imparted by driving machine, and a cap for the said mold closing its lower end, the said cap being provided with means for releasing pressure within the mold upon reduction of pressure exteriorly thereof.

80 7. An apparatus for forming concrete piles comprising, in combination, a concrete retaining form and a pressure mold adapted to be enclosed by the retaining form and having at least one

end in close engagement with the interior of the retaining form, the retaining form and mold being adapted to be driven together into the location of the pile to be formed, and a removable cap secured over the aforesaid end of the mold, and provided with at least one aperture fitted with a removable plug, whereby upon reduction of pressure in the retaining member upon withdrawal of the mold therefrom properly to introduction of concrete into the retaining form, the aforesaid plug will be withdrawn by the resulting difference in pressure between the interior and exterior of the mold, the pressure within the mold being released thereby and drawing up of foreign material into the retaining form prevented.

85 8. An apparatus for forming concrete piles, comprising a mold for the concrete, the mold being formed of a hollow pressure member adapted to be driven into a suitable body of concrete for compression of the concrete into the mold under impact of driving blows imparted thereto, the said mold being provided with pressure releasing instrumentalities for releasing the pressure built up during driving operation, and being further provided with means for readily attaching a pressure meter to the mold for the determination of interior pressure thereof at any time.

90 9. An apparatus for forming concrete piles, comprising, in combination, a concrete retaining form and a pressure mold adapted to closely fit into the retaining form, the said pressure mold having upwardly converging sides, the mold and form being each provided with instrumentalities enabling simultaneous driving of the form and mold into the position to be occupied by the pile, and to enable engagement of withdrawing means for withdrawing the mold and form subsequently to the pile making operations.

95 10. Apparatus for forming piles from plastic material such as concrete and the like, which comprises a hollow retaining form for receiving the material and adapted to be driven into the ground where the pile is to be located, and a hollow mold adapted to be inserted into the retaining form and having the shape and dimensions of the finished pile, the mold being provided with means whereby it may be rammed into the material in the retaining form to compress the said material into the mold to form the pile in a self-sustaining condition.

110 11. A method of forming concrete piles in situ which comprises sinking into the location which the pile is to occupy, an outer concrete retaining shell, filling the shell to the desired extent with concrete, introducing onto the concrete a conical pile-forming mold, driving the mold around the concrete, thereby subjecting the concrete in the mold to progressive lateral pressure to extrude the major part of the moisture content thereof, leaving a substantially hard disintegration-resistant pile, removing the mold and shell, and allowing the pile to set.

115 12. A method of forming concrete piles in situ, which comprises compressing in a lateral direction a mass of concrete into the desired form of

the pile in the position which the pile is to occupy, the compressing being performed by superposing a tapering mold relatively to the mass of concrete and driving the mold around the concrete 5 to thereby compress the said concrete laterally inwardly.

13. A method of forming concrete piles in situ, which comprises compressing, in a lateral direction, a mass of concrete into the desired form 10 of the pile in the position which the pile is to occupy, the compression being performed by superposing a tapering mold relatively to the concrete mass, and progressively driving the mold around the concrete to thereby progressively compress 15 the said concrete, throughout its entire mass, laterally and towards the longitudinal axis of the mass.

14. The method of forming concrete piles in situ, which comprises the steps of placing a mass 20 of concrete in the desired position for formation of the pile, and shaping the mass to pile form by lateral compression of the mass toward the longitudinal axis of the same to extrude the major

portion of the moisture therefrom and create a dense and stable condition prior to setting of the concrete.

15. The method of forming concrete piles in situ, which comprises the steps of placing a mass 80 of concrete in the desired position for formation of the pile, and shaping the mass to pile form by progressive lateral compression of the mass toward the longitudinal axis of the same to extrude the major portion of the moisture therefrom and create a dense and stable condition prior to setting of the concrete.

16. The method of forming concrete piles in situ, which comprises the steps of placing a mass 85 of concrete in the desired position for formation of the pile, and shaping the mass to pile form by combined lateral compression of the mass toward the longitudinal axis of the same, and longitudinal compression, whereby to extrude the major portion of the moisture therefrom and create a dense and stable condition prior to setting of the concrete.
